UNITED STATES PATENT OFFICE

HENRY E. EARLE, OF DANBURY, CONNECTICUT.

HYDRANT AND FIRE-PLUG.

SPECIFICATION forming part of Letters Patent No. 353,739, dated December 7, 1886.

Application filed March 18, 1886. Serial No. 195,630. (No model.)

To all whom it may concern:

Be it known that I, HENRY E. EARLE, a citizen of the United States, residing at Danbury, in the county of Fairfield and State of Connecticut, have invented certain new and useful Improvements in Hydrants and Fire-Plugs; and I do hereby declare the following to be a full, clear, and exact description of the invention, such as will enable others skilled in the art to which it appertains to make and use the same.

My invention relates to improvements in hydrants and fire-plugs; and the object is to produce a hydrant or fire-plug in which the entire operating parts are arranged at the bottom, and thereby the liability of freezing is prevented; also, to provide a means by which the waste water can readily escape and is got rid of; furthermore, to reduce the operating parts to a minimum, and thus simplify the construction; and, finally, to render the operation positive and reliable.

My invention consists in the construction of certain details and arrangement of parts, as will be more fully described hereinafter, and specifically pointed out in the claim, reference being had to the accompanying drawings and the letters of reference marked thereon.

Like letters of reference indicate similar parts in the different figures of the drawings, in which—

Figure 1 represents a vertical cross-section of my improved hydrant or fire-plug. Fig. 2 is a cross-section on line $\alpha\alpha$ of Fig. 1. Fig. 3 is a cross-section on line yy of Fig. 1. Fig. 4 is a vertical section of the valve and operating-screw. Fig. 5 is a similar view of the same in detail.

In the drawings, A represents the main body or stock of the hydrant, made of any suitable size, and is provided at its upper end with the discharge-nozzle B and a stuffing-box, C, for the valve stem or rod D. This valve-stem is preferably made in sections, and is connected to the operating-screw E, which is seated and moves in the valve-box F. The valve-box is provided with the branch passage or side port, G, connected by the transverse

ports g with the cylindrical part f of the valve-box at the upper and lower end.

About midway of the valve-box, and communicating with an annular recess, is a port, h, through which any waste water can escape, and out through the openings or holes e.

The valve consists of the piston H, attached to the screw E by a swivel, h, and to the lower end of the piston the disk-valve I is secured, and when the hydrant is closed said valve is seated on the seat i. An elbow, K, is secured to the lower end of the valve-box, and contains a valve, L, which is guided in its place by a guide, l, secured in the bottom of the elbow. The valve L is forced open by a stem, h', on the piston H, and when released from pressure it is forced against its seat by the water-pressure from the water-main. This is a very important feature of my invention in connection with the piston-valve and operating-screw.

The hydrants or fire-plugs can be made of any desired size, and may be made of any suitable material; and it will be readily understood by those skilled in the art that there is no liability of their getting out of order. The parts are reduced to a minimum in number. The operating parts are all contained in the valve-box, which, by being placed entirely below the surface of the ground, obviates any possibility of freezing, and thereby becoming inoperative or liable to be broken. There is no possibility of waste water remaining in the cylinder part of the valve-box, as all will have to escape through the outlet-openings in the side of the valve-box; and, finally, the packing or wearing parts can be readily replaced whenever required.

The operation is as follows: When the valve I is raised from its seat by operating the screw in the valve-box by means of the valve-stem or operating-rod, the water will flow around the valve L, and passes through the ports g and branch passage G, and up through the hydrant-stock and its discharge-nozzle. When the hydrant is closed, any waste water that may have accumulated above the piston-valve H can freely escape through the side openings,

e, in the valve-box. It is also well adapted for a street-washer or sill-cock.

Having thus described my invention, what I claim, and desire to secure by Letters Patent, 5 is—

The combination of a valve-box having ports *g* and *h*, communicating with side passage, *G*, and annular recess, and containing the operating screw and valve *H*, having the disk-

valve *I*, and stem *h'*, with the valve *L* in the elbow *K*, all arranged substantially as and for the purpose specified.

In testimony whereof I hereby affix my signature in presence of two witnesses.

HENRY E. EARLE.
